UNITED STATES PATENT OFFICE.

HARRY MORRIS, WILLIAM SAPHIER, AND JOHN P. MANN, OF CHICAGO, ILLINOIS,
ASSIGNORS TO HARRY MORRIS AND JOHN P. MANN, COPARTNERS DOING BUSINESS
UNDER THE NAME AND STYLE OF MORRIS, MANN & REILLY.

GARMENT.

1,054,981.

Specification of Letters Patent.

Patented Mar. 4, 1913.

Application filed July 31, 1911. Serial No. 641,476.

To all whom it may concern:

Be it known that we, HARRY MORRIS, a subject of the King of England, residing at 4738 Grand Boulevard, WILLIAM SAPHIER, 5 a subject of the King of Roumania, residing at 4335 Prairie avenue, and JOHN P. MANN, a citizen of the United States, residing at 6052 Kimbark avenue, all of the city of Chicago, in the county of Cook and State of Illinois, have invented new and useful Improvements in Garments, of which the following is a specification.

This invention relates to improvements in ladies' garments, and more particularly to 15 certain novel means employed in ladies' waists for preventing perspiration from soiling such garments.

The invention consists, in general terms, in placing within, and permanently attaching 20 to such a garment, a pair of impervious, or water-proof members, designed to be interposed between the wearer's body under the arm-pits, and the garment, and to prevent perspiration from reaching the latter; 25 and in placing over such impervious members, and in engagement therewith, other, absorbent members, which latter are made of washable material and are designed to permit of ready engagement with, and dis- 30 engagement from said impervious members; whereby they may be interposed between the body and such impervious members and allowed to absorb perspiration, and then removed, washed, and replaced—during all 35 of which time the said impervious members are left permanently in place in the garment, and serve the double purpose, when the absorbent members are also in place and the garment is in use, of retaining the latter in 40 place and also preventing their absorbed moisture from reaching the garment and soiling the same.

A form of device embodying the principles of the present invention is shown in the 45 accompanying drawing, in which:

Figure 1 is a view in perspective with parts broken away showing the complete device as used in connection with a lady's 50 waist. Fig. 2 is a view in perspective showing the complete device detached therefrom. Fig. 3 is a view in perspective showing the detachable cover portion of said device. Fig. 4 is a fragmentary view of a portion of the permanent, impervious member of the

device, showing a modified form of construction. Fig. 5 is a view similar to Fig. 4, showing still another modified form of such construction.

As shown in said drawings, in Figs. 1 to 3 both inclusive, the device which, with its improved means of attachment to the garment embodies the principles of the present invention, comprises essentially an inner, impervious, or water-proof member 7, and an outer, detachable, absorbent member 8; 65 each being somewhat crescent shaped in outline and comprising two lobes or folds, joined together along their upper and shorter curved margins. In the use of the device the said inner member 7 is placed 70 permanently in the garment, being arranged with one of its folds, 9, extending downward into the sleeve thereof and the other fold, 10, extending into the body portion of such garment. This is illustrated in Fig. 1 where 75 it will be noted that the upper and shorter curved edge of said member 7 conforms to the curve of the sleeve opening into the garment; and said member is so secured therein by sewing or otherwise. The two folds 80 9 and 10, are made of suitable impervious or water-proof material and as here shown are made of the material known as "rubberized cloth," comprising a sheet of cloth coated with a covering of rubber. The free edges 85 of the folds 9 and 10, are bound with strips of binding material 11, 11. This part of the device is adapted to be placed within the garment and permanently attached thereto, being arranged therein as above indicated, and being maintained in place in any 90 convenient manner, but preferably by sewing through its upper corner portions, as indicated by the stitches 14. In connection with the permanent member 7 is used the 95 detachable, porous, absorbent cover 8, of similar shape but slightly larger, and likewise comprising two lobes or folds, 16 and 17. This latter member is made of any suitable absorbent cloth and is shown as likewise bound around its free edges by strips of binding material, 18, 18. As a means of securing it in place over the permanent member 7 there are provided upon the inner surfaces of each fold 16 and 17, ribbons or 100 bands 19 and 20; each of such folds having on its inner surface a band 19 extending horizontally across its entire upper width 105

and attached at the margins of such fold; and another band 20 attached at its upper end to the center of the first band and extending downward to the lower margin of 5 the fold, where it is likewise attached. It will thus be seen that the detachable cover 8 may be secured in position over the permanent member 7 by inserting the two folds 9 and 10 of the latter into the pocketlike spaces 10 between the folds 16 and 17 and the bands which cross their inside surfaces; and that no sewing whatever is required upon or in connection with the covering member 8 in order to secure it effectively in place, without 15 wrinkling, within the garment, and in its operative relation to the part 7.

In the practical application of the above described device it is intended that a pair of the members 7 shall be permanently 20 placed within a garment in the manner above described and one or more pairs of the absorbent covering members 8 used in connection therewith. The latter may then be placed into the garment and used as desired; and may readily be removed, washed and replaced from time to time without disturbing the permanent attachment of the inner parts 7 or their function in preventing moisture absorbed by the covering members 30 8 from reaching the garment; and without the necessity of sewing or other time-consuming methods of attaching to such garment. It will be observed moreover, that the construction of the parts being such that 35 the only fastening means between the inner and the outer members are the bands 19 and 20 attached to the outer member 8, the latter is equally adapted for use as a detachable cover for other forms of garment protectors or dress shields such as are commonly 40 found on the market. In any case therefore, where a garment may be provided with a complete dress shield of any ordinary form, embodying one or more plies of impervious 45 fabric in its construction, and it is desired that the shield shall remain in the garment, one of the covering members 8 may be provided and placed over such shield, and subsequently removed, washed and replaced in

the same manner as above indicated; during 50 all of which time the original dress shield may remain within and permanently attached to the garment and serve the same double function as the member 7 above described, in retaining the detachable cover 55 in place and preventing its absorbed moisture from reaching the garment and soiling the same.

In Fig. 4 is illustrated a modified form, 22, of the permanent or impervious member 60 of the device, such member 22 being shaped to provide outward extensions 24, 24, at its upper corners for the purpose of affording a means of attachment to the garment without the necessity of puncturing any 65 portion of the effective surface of such member; it being designed that the sewing shall be through the portions 24, 24, which extend beyond the margins of the absorbent covering member 8.

In Fig. 5 is illustrated another modified form, 26, of the permanent member which is likewise provided with extensions 28, 28 at its upper corners, which extensions also overlap the corners of the member 26 and 75 reinforce the same, in order to prevent the stitches from tearing out under strain.

We claim as our invention:

A garment protector comprising an inner non-absorbent member adapted for permanent attachment to a garment, and an outer removable absorbent member adapted to completely cover said first named member and provided with narrow crossing bands on its under surface within which 85 said non-absorbent member is adapted to lie, whereby said outer member is removably connected to said inner member, for the purpose set forth.

In witness whereof, we have hereunto subscribed our names in the presence of two witnesses this 28th day of July, 1911.

HARRY MORRIS.

WM. SAPHIER.

JOHN P. MANN.
